UNITED STATES PATENT OFFICE

2,436,701

GREASE-GUN HEAD CONSTRUCTION

Edwin P. Sundholm, Albert City, Iowa

Application June 20, 1946, Serial No. 678,123

2 Claims. (Cl. 222—383)

1

The present invention relates to certain new and useful improvements in grease-guns of the lever type generally shown in my Patent No. 2,218,363, issued October 15, 1940, and it relates more particularly to a new and useful construction in the "head" of such grease-guns, namely, that part of the grease-gun which includes the high-pressure cylinder and the cap-like or cup-like socket which receives the reservoir-barrel of the grease-gun.

The object of the present invention is to provide a "head" construction which will reduce the number of parts required for the construction and assembly of a "head" of the type shown in my Patent No. 2,218,363, which will reduce the cost of manufacture of same, and which will make the resultant "head" more durable and leak-proof, and which will permit of a larger intake-port into the high-pressure cylinder-bore, so as more effectively to enable the grease-gun to handle the more viscous and stringy greases and greases at the lower winter-temperature at which most greases become viscous.

The present invention contemplates the fusing or welding of the steel high-pressure cylinder to the pressed-steel cup-like barrel-receiving socket, in one of several alternative forms of construction, with an inlet-port drilled or bored through the weld or fusion; such inlet-port being relatively large (compared to the transversal dimension of the cylinder block), so as to permit free intake of viscous or stringy greases.

In the accompanying drawings in which like reference characters indicate like parts,

Figure 1 represents a perspective view of a lever-type grease-gun having a head embodying the present invention.

Figure 2 represents a cross-sectional view of the head on line 2—2 of Figure 1, with the handle and handle-links omitted and with part of the reservoir barrel broken away.

Figure 3 represents a rear elevational view of the "head," after the reservoir "barrel" has been detached therefrom, as would be viewed in the direction of the arrow 3 in Figure 2 (with the annular barrel-sealing gasket removed from the cap).

Figure 4 represents a cross-sectional view on line 4—4 of Figure 3, prior to the assembly of cap and cylinder-block, showing one mode of construction.

Figure 5 represents a similar cross-sectional view, on line 4—4 of Figure 3, showing another mode of construction in which a thin layer of sil-

2

ver-solder or brazing-metal is intermediate the matching surfaces of cap and block.

Figure 6 represents a perspective view of another form of cap member.

5 Figure 7 represents a cross-sectional view on line 7—7 of Figure 6.

Figure 8 represents a perspective view of another form of cylinder-block.

10 Figure 9 represents a perspective view of another form of cylinder-block.

Figure 10 represents a cross-sectional view on 10—10, Figure 2.

Figure 11 represents the rear elevational view of a cap and cylinder-block assembly, prior to the 15 drilling of the intake-ports.

Figure 12 represents a cross-sectional view on line 12—12 of Figure 11.

20 Figure 13 represents a view similar to that shown in Figure 11, showing an annulus-shaped spot-weld around the intake-port-zone.

Figure 14 represents a cross-sectional view on line 14—14 of Figure 13.

25 Figure 15 represents a perspective view of another cup-shaped barrel-receiving socket with two weld-projections.

Figure 16 represents a cross-sectional view on line 16—16 of Figure 15.

The present invention may be applied to 30 grease-guns of the general type disclosed in my Patent No. 2,218,363, as well as to grease-guns having details or features of construction different from those shown in my Patent No. 2,218,363. Therefore, reference may be had to my Patent No. 2,218,363 merely to exemplify the details of 35 one form of grease-gun to which the present invention is applicable, and for that reason the details of the grease-gun shown in the accompanying drawings are not described insofar as they may be the details of the grease-gun of my 40 Patent 2,218,363 or insofar as such details may be of any conventional form or construction. Insofar as details of the grease-gun shown in the accompanying drawings are not particularly described herein, they may be assumed to be the 45 same as those shown and described in my Patent No. 2,218,363, or may be assumed to be of any conventional form of construction.

In constructing the "head" shown, generally in Figure 1, I either provide a continuous weld or 50 fusion between the flat side 11 of the cylinder-block 12, and the flat outer face 13 of the cap 14 as indicated in Figure 5, or I may provide two or more restricted or limited fusion-areas or weld-areas, one in the zone of the intake-ports 15 and 55 one spaced a distance therefrom, as at 16, as

shown in Figures 2, 3, 4, 6, 7, 8 and 9, and as at 20, indicated in Figures 11, 12, 13, and 14, and as at 23, shown in Figures 15 and 16.

Both the cylinder-block 12 as well as the cap 14 are preferably (though not necessarily) made of steel, as in the case of the grease-gun construction of my Patent No. 2,218,363; the cylinder-block 12 being preferably of square or slightly oblong-rectangular cross-sectioned cold-rolled steel bar-stock, while the cap 14 is preferably pressed-steel; although the cap can be formed entirely by machining out of bar-stock, or otherwise made. The cylinder-block may also be otherwise formed.

The cylinder-block and cap may be affixed to each other by interposing a thin sheet 17 of silver solder, as shown particularly in Figure 5, before the intake-ports 15 are drilled either through cap 14 or through the cylinder-block 12, and the block and cap, so assembled in relation to each other, are then heated to a fusion temperature by induction-heating or by high-frequency electrical heating or by heating on a gas flame or an electrically heated or gas-heated furnace, until the parts are united by fusion through the intermediate solder or brazing layer. Suitable flux may be used to facilitate this union.

Thereafter, the intake-ports 15 are drilled through both cap-wall and through cylinder-wall, as indicated in dotted lines in Figure 5.

The intake-port 15 (which constitutes the passageway for the ingress of grease) is thus formed directly of the metal of the cap-member and of the metal of the cylinder-block, without any tubular bolt (such as the tubular bolt 52 in Patent 2,218,363) to form the grease-passageway. The intake-port 15 intersects the cylinder bore 25 in the high-pressure cylinder-block 12, as shown more particularly in Figure 2.

The outlet opening or discharge-port 18, at the other end of the cylinder-block, may be drilled and tapped before or after the fusion operation just described, or before or after the spot-welding or projection-welding operations hereinafter described.

Instead of silver solder, I may use any other solder or brazing compound which will fuse onto metal of the cap and the metal of the cylinder-block (with suitable flux).

Instead of interposing a thin sheet of silver solder or other solder or brazing material between the flat surfaces 11 and 13 of block and cap, I may flow solder material between them, after the parts have been heated to suitable temperature (with suitable flux between the surfaces; such silver solder or other solder being flowed between the surfaces at a suitable temperature by capillary action).

Instead of using any solder or flux, I may spot-weld or projection-weld the block and cap to each other (preferably before the intake-ports 15 are drilled), by spot-welding either a solid area 19, of generally circular shape, and of a diameter somewhat larger than the diameter of the intake-ports 15, and also a smaller solid area 20, as shown in Figures 11 and 12 or by spot-welding a ring-like or annulus-like area 21, and a smaller solid area 20, as shown in Figures 13 and 14; the annulus 21 having an inner diameter approximately equal to the diameter of the intake-ports 15, so that such intake-port may be drilled through the annulus.

In effecting the spot-welds shown in Figures 11 to 14 inclusive, the welding electrode which is brought to bear against the inner flat surface of

the cap 14, is provided with a contact-area surface or zone generally the same shape and size as the corresponding spot-weld indicated in Figures 11 to 14 inclusive.

5 Instead of merely spot-welding to each other the two flat surfaces 11 and 13 of block 12 and cap 14, I may projection-weld the two to each other either by one or two projection-welds, namely, by projection-welding the two to each other in the zone of the intake-ports 15, while spot-welding in the zone 16, or projection-welding in both these zones.

15 In projection-welding in the zone of the intake-ports 15, I may projection-weld a solid circular area of a diameter sufficiently greater than the diameter of the intake-ports so as to leave an annulus-shaped weld-area surrounding the intake-ports after they have been drilled through the solid projection-weld, as shown in Figures 6, 7 and 8, or, in the alternative, I may projection-weld an annulus through which the intake-ports may thereafter be drilled, as shown in Figures 2, 3, 4, 9, 10, 15 and 16.

20 Thus, as shown in Figures 15 and 16, I may press an annulus or annular rib 22 outwardly in the zone around the intake-ports, and a smaller solid projection-weld area 23 spaced therefrom, so that a single electrode of a contact-area encompassing both weld-projections 22 and 23 may be used to projection-weld the cap to the block.

25 In the alternative, shown in Figures 2, 3 and 4, an annular projection-weld 22 is provided in the zone surrounding the intake-ports 15, while a spot-weld is provided at 16.

30 The weld-projections may project outwardly (from the surface to be projection-welded) by any suitable amount, as, for instance by .015" to .020", more or less.

35 The weld-projections 22 and/or 23 and/or 24 may be either formed by pressing out of the cap, by suitable formations in the punch and die or forming dies which shape the cap, or they may be formed on the block 12 or cap 14 by machining the block or cap, or otherwise forming the projections out of the block or cap, as shown in Figures 6 and 7 as to the cap, and in Figures 8 and 9 as to the block.

40 The block 12 may be of square cross-sectioned bar-stock, as, for instance, $\frac{3}{4}$ of an inch on each side, in which event I am enabled to form $\frac{1}{8}$ inch intake-ports 15 through the cap and through the side-wall of the cylinder-block, or I may use a block slightly oblong in cross-section as shown particularly in Figure 10, with the long side of the cross-section (being, for instance, $\frac{3}{4}$ of an inch), facing the flat surface of the cap, and with a short side of the cross-section (for instance, $\frac{1}{4}$ of an inch) at a right angle to the flat surface of the cap. In this case I can form an intake-port of $\frac{5}{8}$ of an inch in diameter, or even slightly greater in diameter. In either event, the weld-area in the zone of the intake-ports 15, or surrounding the intake-ports 15, will be sufficiently greater, to leave a weld annulus surrounding the intake-ports (whether solder-fused, brazed, spot-welded or projection-welded).

45 It is to be understood, of course, that where the word "fused" is used in the claims, it is intended to comprehend the fusion of the cap and block to each other, whether with or without the intervention of a brazing metal, or a solder, such as silver-solder or soft-solder. It is also intended to comprehend the direct fusion of cap and block to each other, as, for instance, the electrical-resistance weld-fusion of cap and block to each

other or the solder-fusion or brazing-fusion of block and cap to each other, through the intervention of brazing metal or a solder, and also the arc-welding of cap and block to each other along their common boundaries.

Instead of drilling the intake-ports through cap and block after the fusion of block and cap to each other, I may drill the intake-ports through the cap or through the block, or through each, prior to the welding or fusion of block and cap to each other.

It is to be understood, of course, that the dimensional relationships shown in the drawings in respect to the weld-projections is somewhat exaggerated and disproportionate, that is, not shown in true proportion, because, for the purposes of greater clarity in illustration it was found desirable to exaggerate the weld-projections.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having described my invention, I claim the following:

1. A grease-gun head for lever-type hand-operated grease-guns, said head comprising a flanged, pressed sheet-metal cap-member and a relatively thick-walled metal cylinder-block having a cylinder-bore therein whose length is generally co-extensive with the diameter of said cap-member and having a discharge-port near one end thereof, said cylinder-block and said cap-member having contiguous matching surfaces and disposed with their axes generally at a right angle to each other, an intake-port through said cap-member in a direction generally parallel to the axis thereof, an intake-port in one side of said cylinder-block in alignment with the intake-port in said cap-member and extending directly

into and intersecting said cylinder-bore; the metal of said cap-member and the metal of said cylinder-block in the zone of the intake-ports thereof forming the surfaces of the passageway for ingress of grease and said member and block being united by fusion in an area completely surrounding said intake-ports.

2. A grease-gun head for lever-type hand-operated grease-guns, said head comprising a flanged, pressed sheet-metal cap-member and a relatively thick-walled metal cylinder-block having a cylinder-bore therein whose length is generally co-extensive with the diameter of said cap-member and having a discharge-port near one end thereof, said cylinder-block and said cap-member having contiguous matching surfaces and disposed with their axes generally at a right angle to each other, an intake-port through said cap-member in a direction generally parallel to the axis thereof, an intake-port in one side of said cylinder-block in alignment with the intake-port in said cap-member and extending directly into and intersecting said cylinder-bore; the metal of said cap-member and the metal of said cylinder-block in the zone of the intake-ports thereof forming the surfaces of the passageway for ingress of grease and said member and block being united by fusion in an area completely surrounding said intake-ports, and said member and block being further united by fusion in an area near the discharge end of said cylinder-block.

EDWIN P. SUNDHOLM.
